UNITED STATES PATENT OFFICE.

CHARLES D. BONSALL, OF NEW KENSINGTON, PENNSYLVANIA, ASSIGNOR TO UNION METAL PRODUCTS COMPANY, OF CHICAGO, ILLINOIS, A CORPORATION OF DELAWARE.

DEVICE FOR OPERATING CAR COUPLERS.

Original application filed October 24, 1924, Serial No. 745,635. Divided and this application filed September 28, 1925. Serial No. 59,688.

This particular invention relates to what is generally known in the art as a rotating type of uncoupling device for car couplers and comprises an operating rod revolvably mounted on the car with brackets or in any other convenient manner, which rod is usually bent downwardly at the outer end to form a handle, and is bent outwardly at its inner end to form a crank, projecting over the coupler, which crank is provided with a horizontally positioned eye with its axis perpendicular to the longitudinal center of the car. The standard vertical plane coupler has a knuckle pivoted to the coupler head and provided with a tail behind which the lock is placed. The lock lifter protrudes through and above the coupler head and is provided with a horizontally positioned eye. This lock lifter eye is $1\frac{1}{16}$ " in diameter and its axis is perpendicular to the longitudinal center of the car. This size and position has been determined by the American Railroad Association and is standard for the majority of couplers now in service.

My invention resides in the connection between the eye on the crank of the operating rod and the eye on the coupler lock lifter. When the handle is raised the rod is revolved and the crank is thereby raised which unlocks the couplers by raising the lock lifter.

The coupler moves backwardly and forwardly longitudinally of the car in buffing and draft and also moves sidewise in rounding curves, etc., and the connection between the coupler and the operating rod must permit such movements without the component parts becoming disengaged from each other or from either the coupler or the operating rod. It is frequently necessary to uncouple cars when they are coupled together and in contact so that it is impossible to throw the knuckle of either coupler. To meet this condition couplers are designed to assume a "lock set position" wherein the lock lifter can be raised from behind the tail of the knuckle and retained in such a position by means within the head of the coupler independent of the operating rod. This allows the operating rod to fall close to the lock

lifter. To accommodate such a movement the connection between the operating rod crank and the coupler must fore-shorten, which is accomplished by making it of several parts which collapse by means of a hinge joint. The operating rod, as above described, is old and in use on hundreds of thousands of cars now in existence. Such rods had a short chain connecting the crank arm to the lock lifter of the coupler which chains proved unsatisfactory and were responsible for a little more than half of the defects for uncoupling mechanisms reported by the Interstate Commerce Commission. These chains were defective because they were broken, missing, kinked or either too long or too short.

One of the objects of this invention is to provide a connection between the rod and the coupler which will eliminate the defects of the old chain and meet all service conditions required.

These short chains were broken by falling behind the coupler horn and being smashed between the coupler horn and the striking casting by impact of the cars in coupling. The device is designed so that the component parts cannot become disconnected from each other or from the operating rod or the coupler. The connection between the component parts and also their connections to the operating rod and the coupler are such that the device cannot become "kinked." Formerly when a brakeman wanted a small chain to repair one of the old connections he simply guessed as to the amount of chain required and applied it to the car, which accounts for the number of "too long" and "too short" chains reported by the commission. This is not possible with my device.

Another object is to provide a connection which may be hooked into the eye of the coupler lock lifter with the hooked member connected to the crank of the operating rod by another member which permits it to adapt itself to the various service movements of the coupler but prevents it from becoming disengaged from the lock lifter in service.

Another object of the invention is to provide a device wherein the component parts are identical and duplicates, therefore, interchangeable. Duplication, of course, also 5 simplifies manufacture, handling, accounting, etc.

Another object of the invention is to provide a device which can be assembled at the point of manufacture and shipped as a unit 10 to the point of application to a car and which can be applied to the car by a very simple operation which requires no special tools or appliances.

Another object is to obtain a device where- 15 in the component parts are duplicates so that they cannot be wrongfully applied to the car or to each other.

In the drawings:

Fig. 1 is a perspective view of a portion 20 of a car with my invention applied thereon.

Fig. 2 is an elevation of the connector.

Fig. 3 shows the connector in its shortest position.

Fig. 4 shows the connector in its longest 25 position.

Fig. 5 shows the connector in assembled open position.

Fig. 6 shows the connector in closed position and partially collapsed.

Fig. 7 shows one of the members in detail.

Fig. 8 is a detail of the hook to show the lips and notches for retaining the members in a closed position.

In a railway car the operating rod 1 is 30 mounted on the end sill 2 by brackets 3. The usual operating rod had a handle 4 and a crank arm 5 which arm has a horizontally disposed eye 6. The lock lifter 7 of the coupler 8 also has a horizontally disposed eye 9 and my invention resides in a connector for these two mentioned eyes.

The device comprises two pairs of complementary hooked and preferably duplicate members 10. The members of each pair are 45 shaped to be positioned opposite each other to form a closed eye.

The two upper members may be hooked into the eye 6 of the operating crank arm and moved opposite to each other to form 50 a closed eye. The two lower members may likewise be hooked in the eye 9 of the coupler lock lifter and moved opposite to each other to form a closed eye. The two pairs of members (upper and lower) are then connected together by pivot 11. So that the device may be shipped as a unit from the factory it may be advisable to fasten the four component parts together by the rivet 11 (which is a pivot) so that the pairs of members 55 may move to open position, as shown in Fig. 5, for connection to the crank arm and lock lifter, respectively, and then move to closed position, as shown in Figs. 2 and 6. The members are held in position by the lips 11 which have slits 16 on either side

of them so that they may be bent to engage the corresponding notches 17. (See Fig. 8.)

Fig. 6 shows how the component parts collapse relative to each other so that the connector may accommodate service conditions. 70 A plurality of aligned holes 12, 13 and 14 are provided for the pivot to furnish means for altering the length of the connector. The vertical distance between the eye 6 on the crank arm and the eye 9 of the lock lifter 75 varies on different railway cars; in fact, the American Railroad Association formally adopted 6½", 8½" and 10½" as standard lengths for such connectors.

Fig. 3 shows the connector in its shortest 80 position, while Fig. 4 shows it at its greatest length.

This is a division of my co-pending application Serial No. 745,635, filed October 24, 1924. 85

I claim:

1. A connector for a railway car coupler and its operating rod comprising two pairs of complementary members, each pair of complementary members pivotally connected 90 by a pin to move opposite each other to form a closed eye, said pin also pivotally connecting said pairs of members together, and means for detachably securing each pair of said complementary members in the position of a closed eye, said members each provided with a plurality of holes arranged to be aligned with the holes in the other members to accommodate the pin so as to vary the 95 length of the connector.

2. A connector for a railway car coupler and its operating rod, comprising a plurality of members, each having a hook at one end and a plurality of aligned holes at the opposite end, said hooks positioned complementarily to move to form closed eyes at the opposite ends of the connector, a pin rotatively engaging a hole in each member whereby the length of the connector may be altered, means for retaining said members in the position of a closed eye, and means to hold said pin in place. 105

3. A connector for a railway car coupler and its operating rod, comprising a plurality of duplicate members, each having a hook at one end and a plurality of aligned holes at the opposite end, said hooks positioned complementarily to move to form closed eyes at the opposite ends of the connector, a pin rotatively engaging a hole in each member whereby the length of the connector may be altered, means for retaining said members in the position of a closed eye, and means to hold said pin in place. 115

4. In a railway car, the combination of an operating rod mounted upon the car having a horizontally disposed eye, a coupler with a lock lifter, a connector therefor comprising two pairs of complementary members, each pair of complementary members pivot- 120 125 130

ally connected by a pin to move opposite each other to form a closed eye, said eyes forming engagements to the lock lifter eye and operating rod, respectively, said pin also pivotally connecting said pairs of members together, and means for detachably securing each pair of said complementary members in

the position of a closed eye, said members each provided with a plurality of holes to be aligned with the holes in the other members to accommodate the pin so as to vary the length of the connector. 10

CHARLES D. BONSALL.
